United States Patent Office.

JOHN A. BOWER, OF MIDDLEFIELD, OHIO.

Letters Patent No. 77,162, dated April 28, 1868.

IMPROVEMENT IN CARRIAGE-LOCK.

The Schedule referred to in these Letters Patent and making part of the same.

TO ALL WHOM IT MAY CONCERN:

Be it known that I, JOHN A. BOWER, of Middlefield, in the county of Geauga, and State of Ohio, have invented certain new and useful Improvements in Carriage-Locks; and I do hereby declare that the following is a full and complete description of the same, reference being had to the accompanying drawings, making a part of this specification, in which—

Figure 1 is a side view of the lock.

Figure 2 is a top view.

Figure 3 is an under side view.

Like letters of reference refer to like parts in the views.

This lock is attached to the under side of the thills, A, fig. 1, and consists of a curved lever, B, fig. 3, one end of which is pivoted to the cross-rail C, which is then carried around under the thill, and proceeds outward far enough to reach the wheels, as shown in fig. 2.

The free end of the lever is kept in connection with the thills by a guide or stay-strap, D. E is a head, connected to the lever by means of a hinge-joint, so that it can be turned up at a right angle with the plane of the lever, as indicated by the dotted lines *a*, fig. 1.

To this head is fixed the rub-iron F, against which the wheel rubs, as will hereafter be shown.

G, fig. 3, is a rod, one end of which is attached to the lever at the point *x*; from thence it is continued along under the under side of the thill, and to which it is attached by staples, H, through which the rod is allowed to play backward and forward, for a purpose presently shown.

Having thus described the construction and arrangement of the lock, the operation of the same is as follows, viz:

The horse on being placed in the shafts, the thill-straps supporting the shafts will, on the carriage descending a hill, draw hard against the end of the rod at I, which, acting on the lever, will cause it to press the head E and rub-iron against the wheels, and thereby prevent them from turning, the degree of pressure being according to the steepness of the hill or weight of the carriage. The pressure thus exerted on the wheels being released, the lock or rub-iron is forced back from them by a spring, J, leaving the wheels free to turn as before.

It will be obvious that by this arrangement, the lock is self-acting, and is immediately applied without the required attention of the driver, and at all times meeting the resistance of the carriage in equal and sufficient power to restrain its movements, according to the varied circumstances or conditions in which the carriage may be placed.

By having the head to which the rub-iron is fixed hinged to the lever, as above described, the carriage can be run backward, or backed, without the lock being exerted upon the wheels, for on reversing the motion of the wheels, the rub-iron and head will be carried upward in the direction of the moving wheel, and therefore will exert no pressure on them; hence the carriage can be backed up without being in any degree obstructed by the action of the lock.

What I claim as my improvement, and desire to secure by Letters Patent, is—

In the brakes for carriages, the levers B B, hinged heads E E, springs J J, and rods G G, as arranged in combination with the thills A A, in the manner and for the purpose substantially as set forth.

JOHN A. BOWER.
